CLAIM

The ornamental design for an adjustable halter, as shown and described.

DESCRIPTION

FIG. 1 is a perspective view of the adjustable halter of this invention.

FIG. 2 is a front elevation view of the invention.

FIG. 3 is a top plan view of the invention.

FIG. 4 is a bottom plan view of the invention.

FIG. 5 is a left side view of the invention.

FIG. 6 is a right side view of the invention.

FIG. 7 is a rear elevation view of the invention; and,

FIG. 8 is a reduced left side view of the invention in use.

The broken line showing of a horse in FIG. 8 is for illustrative purposes only and forms no part of the claimed design.

The dashed lines on the harness represent stitching and are part of the claimed design.
